UNITED STATES PATENT OFFICE.

GUSTAVUS GREEN, OF BEXHILL-ON-SEA, ENGLAND, ASSIGNOR OF ONE-FOURTH TO FRANCIS PELHAM CLINTON HOPE AND ONE-FOURTH TO JOSEPH MILLER, OF BEXHILL-ON-SEA, ENGLAND.

VALVE-OPERATING MECHANISM FOR INTERNAL-COMBUSTION ENGINES.

No. 857,994.

Specification of Letters Patent.

Patented June 25, 1907.

Original application filed September 15, 1905, Serial No. 278,596. Divided and this application filed July 9, 1906, Serial No. 325,384.

To all whom it may concern:

Be it known that I, GUSTAVUS GREEN, engineer, a subject of the King of Great Britain, residing at 49 Reginald road, Bexhill-on-Sea, in the county of Sussex, England, have invented a new and useful Improved Valve-Operating Mechanism for Internal-Combustion Engines, of which the following is a specification.

10 This invention has for its object an improved valve operating mechanism especially applicable to the engines of motor cars but also applicable to internal combustion engines such as are used upon motor launches and the like.

15 It is the object of the invention to provide a simple and efficient form of valve operating gear for use with valves arranged in the cylinder head. Whenever engines have 20 been constructed with valves in the cylinder head it has been the usual practice to arrange a cam shaft for operating the valves across the top of the cylinder or cylinders. This arrangement, however, is inconvenient 25 as it tends to make the valve difficult of access while it would be especially inconvenient in cases where separable water jackets are used on the cylinders.

According to this invention an arrangement 30 is provided whereby the cams can all be arranged close together on a short shaft conveniently close to the end of the crank shaft, while the tappets which work on the cams are mounted on telescoping rods having connections to the valve operating rods.

35 The invention is illustrated in the accompanying drawings in which—

Figure 1 illustrates in side elevation a four-cylinder engine having the valve operating 40 mechanism constructed in accordance with the invention. Fig. 2 shows an end elevation thereof and Fig. 3 is a plan thereof.

Referring to the drawings it will be seen 45 that there are four cylinders *a*, each separately mounted on the engine frame or crank casing *b*, each of said cylinders having the usual trunk pistons operating on cranks on the crank shaft in the usual manner. The pistons and cranks are not illustrated but *c* is 50 the crank shaft.

The engine shown is of the type described in the specification of my patent application

filed September 15th, 1905 Serial Number 278,596 from which the present application is divided, and some of the letters and numerals marked on the parts of the engine, *e. g.*, the letter 'r' on the water jacket and the reference numerals of the circulation pipes correspond with the letters and numerals used in the specification of the United States patent application above mentioned; these parts will not be further referred to in this specification as the invention is not limited to the application of the valve operating mechanism to this particular type of engine, 65 but said mechanism may be applied to any engine having the valves arranged so that they can be operated conveniently by the valve mechanism about to be described.

Each cylinder has admission and exhaust 70 valves arranged at *u*—*u* in the cylinder head, and all of said valves are operated by plungers *d* sliding vertically in guides *e* mounted at the sides of said cylinders near the heads thereof.

75 *f* is a sleeve free to rotate on the shaft *g* which is fixed in the casing *b* and is supported in bracket *h*, said sleeve being driven at half the speed of the crank shaft by suitably proportioned gear wheels *i* or by any other well known means for this object. The sleeve *f* carries all the cams *k* for operating the inlet and exhaust valves, *i. e.*, eight cams in this case. The sleeve may also carry the ignition gear which is not shown in this case as it in 85 itself forms no part of the present invention; any suitable electric ignition apparatus may be used.

Two rods *l*, *l* are carried in bracket bearings *m* and extend longitudinally of the engine, 90 one at each side thereof. On these rods are sleeves or tubes *n* fitting or telescoping one within the other. On each side of the engine the sleeve *n* of smallest section fits closely around the rod *l* and terminates at the right 95 hand end (Figs. 1 and 3) in a tappet *o* operating on one of the cams *k*; at the left hand end this sleeve *n* carries a lever *p* connected by a link rod *q* to the plunger *d* of the left hand cylinder *a*. The sleeve *n* of the next larger 100 cross section works around the first sleeve, operates the plunger *d* of the next cylinder *a* by a similar link rod *q*, and terminates at the right hand end with a tappet lever *o* also

bearing on one of the cams *k*; similarly, for each of the other cylinders toward the right, the sleeves operating the valve plungers embrace the sleeves lying nearer to the shaft. 5 The brackets *m* are large enough where required to bear the sleeves around the rod *l*. All the sleeves are thus separate one from another and each can be separately rocked by its tappet *o* working on its cam *k* and thereby 10 the plungers *d* operating the valves can be drawn down by the action of lever *p* and link rods *q* at the required moment. All the sleeves *n* are freely supported on the rods *l* so that said rods can be moved longitudinally without disturbing the sleeves. Hence 15 the rods may be employed to operate any suitable apparatus. It will be seen that the mechanism above explained makes it possible for all the inlet and exhaust valves of all 20 the cylinders to be independently operated by cams arranged close together on a short half speed sleeve or shaft, and in this way a neater and more compact type of engine can be made. 25 The construction above described makes it easy to adjust the operating mechanism for each valve with great accuracy, as the levers *p* linked to the valve operating plungers may be arranged to be clamped on the ends of 30 their hollow shafts so that they can be independently fixed in the best positions for operation of the valves.

It is convenient to form the heads *d* of the plungers which operate the valves in such a 35 way that they can be turned to one side when required in order that access can be readily obtained to the valves or so that any one or more cylinders can be thrown out of action when required for testing the ignition for example. The heads of the plungers can be 40 locked in their working positions by locknuts *v* or any convenient means or the under surfaces of the heads *d* may be slightly hollowed out to engage with the tops of the valve spindles during working, while the frictional 45

resistance to the turning of the heads *d* is relied upon to prevent said heads from getting out of position when not engaging with the valve spindles.

What I claim is:—

1. In an internal combustion engine the combination of a short lay-shaft, means for driving the lay-shaft from the main-shaft of the engine, cams upon said lay-shaft, telescoping rotary shafts of different lengths 55 each carrying at one end a tappet bearing on a cam, plungers adapted to operate the respective valves of the engine, means for guiding said plungers and connections between the plungers and the respective telescoping shafts.

2. In an internal combustion engine the combination of a short lay-shaft and cams upon said shaft, means for driving the shaft from the engine, two sets of telescoping 65 shafts arranged one on either side of the engine, tappets each connected to one telescoping shaft and bearing on one of the cams, and connections between the respective telescoping shafts and the valves of the engine, 70 whereby the latter are operated at the proper times.

3. In an internal combustion engine, the combination of a lay-shaft with cams thereon, tappets bearing on said cams, sets of telescoping shafts, one set at each side of the engine, each of said telescoping shafts carrying one of said tappets, means connecting the respective telescoping shafts with the respective valves of the engine, and rods extending through the respective sets of telescoping shafts, said rods adapted to be moved independently of said shafts. 75

In testimony whereof I have signed my name to this specification in the presence of 80 two subscribing witnesses.

GUSTAVUS GREEN.
